UNITED STATES PATENT OFFICE

ARTHUR J. BARNETT, OF NEW YORK, N. Y., ASSIGNOR TO THE WORCESTER KNITTING CO., OF WORCESTER, MASSACHUSETTS, A CORPORATION OF MASSACHUSETTS

BATHING SUIT

Application filed July 22, 1929. Serial No. 380,182.

This invention relates to a bathing suit of the one piece variety and the principal objects are to provide an improved way of connecting the jersey with the trunks at the waistline so that there will be no weak spot along the line of sewing and so that there will be a suitable place to attach the loops through which the belt is passed and so that this belt will have an upward pull on the extreme upper edge of the trunks thereby supporting the trunks properly in a one piece suit; to provide an improved waistline which is higher at the center in the back than at the sides so as to procure the necessary fullness at the back of the garment and to provide a one piece suit which can be made simply and with little waste of material of two different materials so that there may be a jersey and trunks of contrasting colors.

Other objects and advantages of the invention will appear hereinafter.

Reference is to be had to the accompanying drawings in which—

Fig. 1 is a front view of a complete bathing suit constructed in accordance with this invention;

Fig. 2 is a sectional view on the line 2—2 of Fig. 1 showing a step in the process of connecting the jersey with the trunks;

Fig. 3 is a similar view showing the completed seam;

Fig. 4 is a sectional view similar to Fig. 3 at another point showing the loop for the belt;

Fig. 5 is a view of the inside in the direction of the arrow 5 in Fig. 3 showing the stitching at the waistline, and

Fig. 6 is a rear elevation of the same suit.

This suit is made of two parts, an upper part, jersey, or shirt 10 and a nether part, or trunks, 11 which may be of contrasting colors and of different qualities of material. The extreme ends of these two parts are made the same as usual and the invention all relates to the region in which these two parts are united at the waistline.

The jersey, instead of going way down below the waistline, is cut off at the waistline horizontally across the front and along a curve across the rear which extends upwardly at the center as shown at 12 in Fig. 6. It is

the jersey part in which the most change is made because this eliminates all parts of the jersey below the waist and removes the bulk of this garment which in some cases is tucked into the trunks and forms bulges and projections under the trunks.

Of course, as it is a skirtless or one piece bathing suit and the skirt part is eliminated, the bottom of the jersey can be sewed to the trunks on the inside of the same. This is done by turning the material for the trunks wrong side out or backwardly and having the upper edge at 13 come down to the lower edge of the jersey and sewing the seam 14 to the two at this point. The material of the trunks is then brought upwardly for perhaps three quarters of an inch from this point all around the bathing suit and doubled over as indicated by reference to Figs. 2 and 3. Then the trunks material 11 is brought down into contact with the end 13 and rows of stitches 15 introduced through the three thicknesses as shown in Figs. 3 and 5. This is shown in the form of a feather stitching to finish the seam and assisting the preventing of the exposure of any raw edges.

It will be seen from this that, above the bottom of the jersey, there extends a loop so-to-speak of the material of the trunks which is doubled over at the top and therefore requires no seam, no cutting and can have no frayed edges. This finishes the bathing suit along the waistline. Loops 16, of the same material as the trunks preferably, are sewed to the garment, as indicated in Fig. 4, by a line of stitches 17 through the top of the loop extending upwardly and a line of stitching 18 through the material of the trunks below the seams 15. This permits of the running of the belt through these loops coming at the top of the trunks and provides a convenient way of attaching these loops.

From what has been said it will be seen that this provides a neat garment having the top of the trunks finished off without any extra seam, saves material in the jersey, avoids the provision of extra material below the waistline under the trunks to bulge the same out of shape and provides the fullness in the

back to avoid restriction of the wearer in bending, swimming and athletic activities.

Although I have illustrated and described only one form of the invention I am aware of the fact that modifications can be made therein by any person skilled in the art without departing from the scope of the invention as expressed in the claim. Therefore, I do not wish to be limited in this respect but what I do claim is:—

10 As an article of manufacture, a one piece bathing suit having an upper part and a nether part of two different pieces of material sewed together by a line of stitches around the waistline, the lower part having the front portion extending above the waistline a material distance and extending downwardly behind the front portion and in front of the upper part where the line of stitches 15 secures it to said upper part forming a loop extending around the garment, and straps for a belt secured at their upper ends to the extreme upper end of the trunks near the fold of the loop thereof and secured at their lower ends to the material of the trunks below the 20 waistline seam.

25 In testimony whereof I have hereunto affixed my signature.

ARTHUR J. BARNETT.
